(57) **CLAIM**

The ornamental design for a vehicle, as shown and described.

DESCRIPTION

FIG. 1 depicts a front, top, left perspective view of a vehicle showing our new design.

FIG. 2 depicts a rear, top, right perspective view thereof.

FIG. 3 depicts a front view thereof.

FIG. 4 depicts a rear side view thereof.

FIG. 5 depicts a left view thereof.

FIG. 6 depicts a right view thereof.

FIG. 7 depicts a top view thereof; and,

FIG. 8 depicts a bottom view thereof.

The claimed design is indicated by the relatively dark portions of the vehicle illustrated in the figures. The relatively light portions show portions of the vehicle that form no part of the claimed design. The dash lines depict boundaries of the claimed design and form no part of the claim.

1 Claim, 8 Drawing Sheets
